MARCEL BIEUVILLE, OF BELLEVUE, FRANCE.

DRAWING APPARATUS UTILIZING PARALLEL MOVEMENTS.

1,408,252.

Specification of Letters Patent. Patented Feb. 28, 1922.

Application filed October 26, 1920. Serial No. 419,766.

To all whom it may concern:

Be it known that I, MARCEL BIEUVILLE, a citizen of the Republic of France, residing at Bellevue, Seine-et-Oise, France, 8 5 Avenue Gallieni, have invented a new and useful Improvement in Drawing Apparatus Utilizing Parallel Movements, (for which I have filed applications in France Oct. 24, 1919, and Jan. 25, 1920, and in Germany 10 Nov. 6, 1919,) of which the following is a specification.

This invention relates to drawing apparatus utilizing parallel movements, the said apparatus consisting of a series of arms 15 pivoted to each other, each arm being a rod, to each of the ends of which is pivoted a pulley, the connection between the said pulleys being ensured by a flexible band say of steel, the first pulley of the first arm 20 being fixed, and the last pulley of the last arm carrying the drawing instrument.

In the apparatus of that kind it is impossible, under the penalty of increasing the weight of the apparatus, to give the rods 25 supporting the pulleys sufficient cross-sections to obtain a perfect rigidity this results in deformations which are transformed into a tension of one section of the flexible band and in a slackening of the 30 other section, which gives rise to errors which sometimes reach several millimeters. Moreover, the band sections not being protected by any part, are liable to be hooked or caught and consequently to interfere with 35 convenient and quick use of the instrument. The present invention relates to a construction of an apparatus which is free from the drawbacks just mentioned.

The apparatus according to the invention 40 is characterized by the fact that each arm, at the ends of which are pivoted the pulleys over which passes the steel band, forms a gear case for the said band, the said gear case can be a single one for the two sections or separate for each section.

The invention relates also to the erecting 45 of the drawing instrument on a part concentric with the head pulley of the apparatus, forming a cover for the said pulley, 50 movable relatively to the same and capable of being locked by the tightening of a screw forming a brake, so that it is possible to give the drawing instrument orientation in any desired direction and to lock it afterwards 55 in the said direction.

The accompanying drawing shown by

way of example various constructions of the apparatus according to the invention.

Figures 1 to 5 relate to a first construction in which each arm is constituted by 60 two shackles connected together by two parallel tubes in the interior of which passes the steel band, the tension of which is obtained by rotating a screwthreaded sleeve arranged on each tube.

Figure 1 is a plan of the whole of the apparatus,

Figure 2 is, on an enlarged scale, a detail view in plan of the head pulley,

Figure 3 is a vertical section on line 3—3 70 of Figure 2,

Figure 4 is a partial horizontal cross-section on line 4—4 of Figure 3,

Figure 5 is a partial vertical section on line 5—5 of Figure 2.

Figures 6—8 relate to a construction of an apparatus in which the two sections of one and the same arm are mounted in the interior of a single gear case.

Figure 6 is an elevation, Figure 7 a horizontal section on line 7—7 of Figure 6 and Figure 8 a vertical section on line 8—8 of Figure 7.

Finally, Figure 9 is a plan of a simplified construction.

Each arm such as A or B is constituted by two tubes a arranged parallel to each other and connected together at their ends by articulation shackles b of stamped out sheet metal, brazed on the said tubes. The pulleys c c' and d d' are pivoted between the branches e of forks forming part of the shackles b. The pulley c is secured to a part f pivoted to a plate g intended to be secured to the drawing table.

The distance between the tubes a is such that the flexible bands which connect together the pulleys c c' and d d', pass without friction in the interior of each of the said tubes.

Towards one of its ends, each tube b carries between it and the hinge shackle, a sleeve h with screwthread with right and left hand screw so as to enable the bands to be tightened.

The head pulley d' (Figures 2 and 3) is hollow and has a cover i; the said cover to which is secured by means of a suitable device the drawing instrument, for instance a set square, is movable about the axis of the pulley d' and can be locked relatively to the said pulley by means of the following de-

vice: On the cover *i* is mounted a screw *j*, the head *j* of which comprises a slot *j*² with which engages a circular projection *k* of the pulley *d*¹; the tightening of the nut *l* of the screw *j* brings about the rising of the said screw and therefore its locking on the projection *k*, which results in locking the cover *i* relatively to the pulley *d*¹.

- To facilitate the operation of the nut, *l*, the latter is provided on its periphery with a set of teeth *m* forming a pinion in engagement with a toothed quadrant *n* also pivoted on the cover *i* and operated by means of a lever *n*¹. A spring *n*² acts on the toothed quadrant *n* so as to produce constantly the locking of the screw *j* on the projection *k*. A slight pressure on the lever *n*¹ produces the unlocking, so as to allow the drawing instrument to be given the desired direction; as soon as the lever *n*¹ has been released, the spring *n*² produces automatically the tightening.

Under the cover *i* is secured a small blade *o* forming a spring, the free end of which has a projection *o*¹ intended to come into engagement with any of the recesses *p* provided in the upper part of the circular projection *k*. These recesses made for instance at intervals of 30°—45° and 60° at either side of the zero, enable the drawing apparatus to be given the desired direction without having recourse to the graduation provided on the cover *i*.

A handle *q* secured to the cover *i* of the head pulley *d*¹, facilitates the working of the apparatus.

To ensure correct contact of the pulley *d*¹ and of its cover, the latter is exposed through the intermediary of a small split cone *r* to the action of a spring *s* arranged round the axis of rotation of the pulley; the split cone *r* is intended to take up for the play of the cover relatively to its axis.

The connection of the cover *i* and of the drawing instrument secured to the head pulley *d*¹, is effected through the intermediary of a screw *t* with a nut *t*¹; the screw secured to the drawing instrument passes through an oval hole *u* so as to make possible a small movement of the drawing instrument relatively to the cover *i*.

According to the second construction, in the centre of the pulley *c* is pivoted a tube *v*, the other end of which carries the pulley *c*¹ of the same diameter as pulley *c*.

The other arm is also constituted by a tube *v*, in the interior of which are mounted the pulleys *d* and *d*¹. The pulley *c* is locked relatively to the plate *g* by means of a screw *c*², and the pulley *d*¹ carries as before the drawing instrument. Tension of the bands secured to the pulleys *c* *c*¹ and *d* *d*¹ is obtained by means of turn-buckles *x*.

The apparatus shown in Figure 9, comprises two bars *y* *y*¹ each secured to a pulley

c; these bars are connected together by means of a pivoted arm constituted for instance by a tube *v* of rectangular cross-section; over the pulleys *c* passes as before a flexible band secured to the rim by any desired means, such as screws etc.

It is obvious that the invention is by no means limited to the constructional details just described; thus for instance the shape of the tubes, the method of stretching the steel bands could be varied, and also the mounting of the drawing instrument on the head pulley of the apparatus.

Claims:

1. A drawing apparatus utilizing parallel movements comprising a drafting board, a pulley, means for securing said pulley in fixed position on said drafting board, a pair of pulleys rotating on the same axis, an arm adapted to pivot on the axis of the fixed pulley, and connecting the fixed pulley and one of the pulleys of said pair, another pulley, a drafting instrument carried thereby, an arm connecting said last named pulley and the second pulley of the pair and adapted to pivot on the axis of each of said pulleys, an endless band passing over the fixed pulley and the first of the pair of pulleys, and another endless band passing over the second of the pair of pulleys and the pulley carrying the drawing instrument, each of said arms encasing its said endless band.

2. A drawing apparatus utilizing parallel movements comprising a drafting board, a pulley, means for securing said pulley in fixed position on said drafting board, a pair of pulleys rotating on the same axis, an arm adapted to pivot on the axis of the fixed pulley, and connecting the fixed pulley and one of the pulleys of said pair, another pulley, a drafting instrument carried thereby, an arm connecting said last named pulley and the second pulley of the pair and adapted to pivot on the axis of each of said pulleys, an endless band passing over the fixed pulley and the first of the pair of pulleys, and another endless band passing over the second of the pair of pulleys and the pulley carrying the drawing instrument, each of said arms consisting of two parallel tubes, shackles connecting the tubes together at each end so that said metal bands can pass therethrough conveniently, said shackles forming axes for the pulleys.

3. A drawing apparatus utilizing parallel movements comprising a drafting board, a pulley, means for securing said pulley in fixed position on said drafting board, a pair of pulleys rotating on the same axis, an arm adapted to pivot on the axis of the fixed pulley, and connecting the fixed pulley and one of the pulleys of said pair, another pulley, a drafting instrument carried thereby, an arm connecting said last named pulley

and the second pulley of the pair and adapted to pivot on the axis of each of said pulleys, an endless band passing over the fixed pulley and the first of the pair of 5 pulleys, another endless band passing over the second of the pair of pulleys and the pulley carrying the drawing instrument, each of said arms consisting of two parallel tubes, shackles connecting the tubes together at each end so that said metal bands 10 can pass therethrough conveniently and

each of said shackles forming axes for the pulleys, and a threaded tightening sleeve on each tube between the latter and one of the shackles on which it is mounted. 15

In testimony whereof I have signed my name to this specification.

MARCEL BIEUVILLE.
